(57) **CLAIM**

We claim the ornamental design for drum-type washing machine, as shown.

DESCRIPTION

FIG. 1 is a front, left side, top perspective view of a drum-type washing machine showing our new design;

FIG. 2 is a front elevational view thereof;

FIG. 3 is a left side elevational view thereof;

FIG. 4 is a right side elevational view thereof;

FIG. 5 is a top elevational view; and,

FIG. 6 is a bottom elevational view thereof.
